Primary Examiner — Elizabeth Albert(74) Attorney, Agent, or Firm — Banner & Witcoff, Ltd.(57) CLAIM

The ornamental design for a handle, as shown and described.

DESCRIPTION

FIG. 1 is a top, front, right perspective view of a handle showing our new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

The long and short broken lines that define the bounds of the claimed design form no part thereof. The even length broken lines are included to show portions that form no part of the claimed design.

1 Claim, 3 Drawing Sheets(56)
